WASHING CONTAINER FOR COMESTIBLES OR THE LIKE

Charles W. Ranson, 7906 Agnew Ave.,
Los Angeles, Calif. 90045

Filed Aug. 17, 1966, Ser. No. 3,497

Term of patent 14 years

(Cl. D44—1)

The dominant features of the design are shown in full lines.

I claim:

The ornamental design for a washing container for comestibles or the like, substantially as shown and described.
